(57) **CLAIM**
The ornamental design for an extra tabs diaper, as shown and described.

DESCRIPTION

FIG. 1 is a perspective view of an extra tabs diaper of my new design shown in use.

FIG. 2 is a perspective front view of the extra tabs diaper with the tabs shown in an accordion-style partially folded position. FIG. 3 is another perspective front view of the extra tabs diaper with the tabs folded as shown in FIG. 2.

FIG. 4 is a perspective rear view of an extra tabs diaper of my new design.

FIG. 5 is another perspective rear view of an extra tabs diaper of my new design.

FIG. 6 is another perspective front view of an extra tabs diaper of my new design.

FIG. 7 is another perspective front view of an extra tabs diaper of my new design.

FIG. 8 is a front elevational view of an extra tabs diaper of my new design.

FIG. 9 is a rear elevational view of an extra tabs diaper of my new design.

FIG. 10 is a top elevational view of an extra tabs diaper of my new design.

FIG. 11 is another top elevational view of an extra tabs diaper of my new design.

FIG. 12 is a bottom elevational view of an extra tabs diaper of my new design.

FIG. 13 is another bottom elevational view of an extra tabs diaper of my new design.

FIG. 14 is a right side elevational view of an extra tabs diaper of my new design.

FIG. 15 is another right side elevational view of an extra tabs diaper of my new design.

FIG. 16 is a left side elevational view of an extra tabs diaper of my new design; and,

FIG. 17 is another left side elevational view of an extra tabs diaper of my new design.

The broken lines showing of the infant is included for the purpose of illustrating environment and forms no part of the claimed design.

1 Claim, 17 Drawing Sheets
